CLAIM

The ornamental design for a multitool, as shown and described.

DESCRIPTION

FIG. 1 is a perspective view of a multitool showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The multitool is shown with a symbolic break in its width. The portion of the multitool between the break lines forms no part of the claimed design.
